UNITED STATES PATENT OFFICE

2,473,445

SPRING CAMBERING MACHINE

George R. Reed, Grosse Pointe Park, Mich., assignor to Eaton Manufacturing Company, Cleveland, Ohio, a corporation of Ohio

Application April 11, 1947, Serial No. 740,945

8 Claims. (Cl. 266—4)

1

This invention relates to springs and more particularly mechanism for producing cambered leaf springs.

Broadly the invention comprehends the provision of power-driven mechanisms for automatically handling leaf spring plates through the stages of heating, cambering, and quenching in properly timed sequence for the substantially simultaneous production of two different spring plates of high quality vehicle leaf springs from the flat plate to cambered state.

It has been the general practice in the past in the heating, cambering, and quenching of leaf spring plates to employ manual handling of the plates in the transporting of same through the furnace, removal from the furnace, and delivery and insertion to the proper die for the cambering thereof. The present invention through the provision of automatically operable mechanism effectively arranged relative to a single furnace and two dies having appropriate timing controls therefor provides for the production of two different cambered leaf spring plates from their flat stage when manually inserted in the furnace to finished, cambered, heat-treated stage without any manual assistance, wherein the two different plates each require a different die for the proper cambering thereof.

An object of the invention is the provision of a machine incorporating automatically operable mechanism for carrying out the heating, cambering, and quenching of leaf spring plates in an efficient and economical manner.

Another object of the invention is the provision of mechanism for automatically transporting heated leaf springs from a heating furnace to a pair of dies in alternating relation for the cambering and quenching of the plates, each of said dies receiving different plates than the other die.

A further object of the invention is the provision of mechanism associated with a heating furnace and two dies for automatically conveying or transporting two different types of leaf spring plates through the heating furnace and for delivering the plates to their respective dies in alternate relation and orderly arrangement for the cambering and quenching thereof.

A still further object of the invention is the provision of combination mechanism for automatically carrying out the heating, cambering, and quenching of two different types of leaf spring plates through the utilization of a novel arrangement of a single heating furnace and two dies, one for each type of plate and mechanism associated with the furnace and dies for proper-

2

ly transporting the plates through the furnace and thence alternately to the dies for the cambering thereof wherein the plates are loaded in prearranged order in the furnace for coordinated delivery by the conveying mechanism to the proper die.

Other objects and advantages of the invention will appear from the following description taken in connection with the drawings forming a part of the specification; and in which:

- 15 Fig. 1 is a fragmentary, partially sectionalized, side elevational view of a furnace and automatic leaf spring plate transporting and delivery mechanism associated therewith;
- 15 Fig. 2 is a top plan view of Fig. 1;
- 20 Fig. 3 is a side plan view of mechanism for transferring the selected leaf spring plates from the rollers of the delivery mechanism to their respective die;
- 20 Fig. 4 is a fragmentary, side elevational view of a die associated with the furnace and delivery mechanism;
- 25 Fig. 5 is a fragmentary end plan view of Fig. 3;
- Fig. 6 is a partially broken fragmentary end plan view of the roller mechanism of the delivery mechanism;
- 30 Fig. 7 is a cross-sectional view of the roller mechanism taken through one of the rollers;
- Fig. 8 is a top plan view of the reversing mechanism for the center section of rollers;
- 35 Fig. 9 is a fragmentary side plan view of the cam mechanism for the lifting means of the transporting mechanism situated in the furnace;
- Fig. 10 is a fragmentary side plan view of the cam mechanism for axially moving the transporting mechanism situated in the furnace;
- 35 Fig. 11 is a side plan view of the micro-switch mechanism associated with the rollers for controlling the delivery means;
- 40 Fig. 12 is an end plan view of Fig. 11;
- Fig. 13 is a cross-sectional view taken along lines 13—13 of Fig. 8; and
- Fig. 14 is a top plan view of the spring plate pusher means shown in Fig. 1.
- 45 The instant invention was devised for the purpose of providing an automatic set up for the heating, cambering, and quenching of two different types of leaf spring plates, each requiring a different die for the cambering thereof through the utilization of a single heating furnace and two dies for the respective different plates arranged appropriately relative to the furnace and having incorporated therewith mechanism for transporting the plates through the furnace, mechanism for removing the plates from the

furnace, mechanism for moving the plates to delivery means therefor, mechanism for alternately delivering the plates in accordance with prearranged loading in the furnace to their respective dies, and mechanism for inserting the plates in the dies, all of said operating mechanisms being automatically switch or cam controlled to provide for the coordinated timed operation thereof. The mechanism for alternating the delivery of the plates to their proper die forms the fundamental concept of this invention in that it provides the connecting link between the furnace and dies permitting the use of one furnace to supply two dies and, as such, consists of rollers which are reversely rotatable by appropriate gearing, clutching, and controls therefor actuated by timing cams effective to cause rotation of the rollers in one direction during one phase of operation for delivery of one type of spring plate to one die and rotatable in the other direction for the delivery of another type of spring plate to the other die.

Referring to the drawings for more specific details of the invention, 10 represents generally a combination mechanism for the automatic handling of leaf spring plates through the steps of heating, cambering, and quenching, comprising a heating furnace 12, a pair of cambering dies 14, associated with appropriate oil quenching tanks 16, a conveyor means 18 arranged in the furnace for transporting the spring plates through the furnace in orderly parallel alignment, mechanism 20 for unloading the plates from the furnace, mechanism 22 for pushing the plates down a suitable slide provided to delivery mechanism 24, said mechanism 24 providing for alternately moving the spring plates in one direction or another for delivery to one die or another, a pair of mechanisms 26, each for association respectively with one of the dies for inserting the plates in the die for the cambering thereof, said dies 14, conveyor means 18, and mechanisms 20, 22, 24, and 26 all being power driven and controlled relative to one another for the coordinated timed operation thereof.

The conveyor means 18 which comprises horizontally arranged arcuately horizontally movable bars 28, cooperable with horizontally arranged vertically movable bars 30 for transporting the spring plates in orderly parallel arrangement through the furnace is more specifically described in my copending United States application, Serial No. 715,747, filed December 12, 1946.

The unloading mechanism 20 includes a plurality of arms 31 movable through a limited arc effective to pick up the plate at the exit of the furnace from bars 28 and 30 and deposit same at a point removed from the bars on slide bars 32.

The mechanism 22 for pushing the plates down the slide bars 32 after removal from the furnace after the heating thereof and for delivering said plates to mechanism 24 comprises a plurality of pusher arms 34 affixed at spaced points upon a longitudinally extended carriage 36 arranged for sliding movement upon rollers 38 attached thereto along rails or tracks 40 supported between the front 42 of the furnace and a vertical support 44 mounted intermediate the quench tanks. The arms 34 are adapted through the provision of suitable lever and linkage 46 to be pivoted in such a way that when the carriage is being pulled away from the furnace, the arms will be in dotted line position effective through the fingers 48 on the ends thereof to push the plates along slides 32 arranged adjacent the exit from the furnace and

mechanism 24. The leverage and linkage 46 is actuated through power driver lever means 50 pivoted at a point on a horizontal support 52 affixed to support 44 effective during the movement of the carriage toward or away from the furnace as the case may be to move the arms 31 to full line position during the course of movement toward the furnace and to dotted line position as it moves away from the furnace. With the arms in dotted line position, the fingers 48 thereof engage the plate deposited on the slides by arms 31 and push the plate down the slides as the carriage is retracted from adjacent the furnace.

The alternate delivery mechanism 24 comprises a plurality of driven rollers 54, 56, and 58 arranged in line with the axes of rotation parallel to one another, said rollers 54 comprising a group located centrally of the rollers 56 and 58 and being driven by reversing mechanism 60 for rotation in either direction depending upon the phase of motion to which the machine is set. The rollers 56 are associated with one of the dies 14 and one of the mechanisms 26 for positive continued rotation in one direction and the rollers 58 are associated with the other die 14 and mechanism 26 for continued rotation reversely to rollers 56.

The mechanisms 26 each include arms 62 adapted to be belt driven from a motor 64 through gearing 66 along rollers 68 effective to pick up the plates delivered to the respective rollers 56 or 58 and deposit the plates in the appropriate die 14 with which the rollers and mechanism are associated between die faces 70 and 72. The course of the arms 62 is governed by movement along a reciprocating chain drive path and by an appropriate cam 14 driven from the motor 64 for effecting the lifting action of the plates from the rollers in the course of their travel to the dies; whereas a cam 76 together with a micro-switch 78, one of which is associated with a set of rollers 56 and 58, operates to control the operation of the motor 64 relative to the timed function of mechanism 26. Cam 80 similar to cam 76 oppositely disposed from cam 76 driven by the same gearing as cam 76 is operable in timed relation to mechanism 26 for the proper timed operation of die 14 after a spring plate has been inserted therein. This operation comprises the closing of the die upon the plate for the cambering thereof as well as the subsequent movement of the die to quenching position for the quenching of the plate in oil tank 16.

The rollers 54 are driven from a motor 82 through an arrangement of gears and clutches 84, including a clutch 86 controlled by a cam 88 and a second clutch 90 controlled by the cam 92 rotatable with the cam 88. The clutches 86 and 90 are adapted to transmit power respectively by way of sprockets 94 and 96 to a double sprocket 98 having gearing connection with one of the rollers 54, said rollers 54 each being geared together by suitable drive and idler gears 100 and 102 respectively. The cams 88 and 92 are driven from a source of power to be hereinafter described and are arranged so as to effect alternate engagement and disengagement of the clutches for the purpose of driving sprocket 98 in one direction or another depending on which clutch is engaged. The rotation of sprocket 98 is imparted to the gear chain 100 and 102 for the rotation of rollers 54 by way of rotatable gear 104 secured to the shaft of sprocket 98. It is to be noted in view of the arrangement of gears 106, 108, and 110, 75 that upon alternate engagement of the clutches

56 and 58 the sprockets 94 and 96 are alternately, positively driven reversely to one another where in the case of clutch 86 being in engagement and clutch 98 being in disengagement, the sprocket 96 will rotate idly with the rotation of sprocket 94 because of its chain drive relation with sprocket 98 and vice versa with regards to the engagement of clutch 98 and disengagement of clutch 86.

Fig. 8 illustrates the arrangement of rollers 54, 56, and 58 respectively with regards to their input drive means; and, as such, it is to be noted that no driving relation exists between the respective sets of rollers.

The rollers 58 are driven from motor 82 by an appropriate chain drive 112 coupled to sprocket 114 which in turn drives a shaft upon which is secured a gear 116 associated for driving relation with drive and idler gears 118 and 120 for driving the rollers in one direction as controlled by the direct operation of the motor. Likewise the rollers 56 are driven from a motor 122 which is drivingly connected to a sprocket gear 124 similar to sprocket 114; said sprocket 124 in turn having a rotatable shaft 126 affixed thereto supporting a rotatable gear 128 having association with drive and idler gears 130 and 132 for driving the rollers 56 in accordance with the rotation of motor 122.

The rollers 56 and 58 at all times rotate in unison with their respective motors 122 and 82, whereas the rollers 54 are controlled for rotation in one direction or another depending upon the desired control thereof.

The rollers 54 are all arranged with the exception of the end two rollers on each side thereof with shoulders 134 away from the rollers for the purpose of restraining the spring plates from being shoved off the rollers when delivered thereto after sliding down slider bars 32. The rollers 56 and 58 are arranged with their shoulders 134 with the exception of two of each set adjacent rollers 54 disposed from the dies and quench tanks so that it is possible for the mechanisms 26 to pick the plates off the rollers without the necessity of lifting them over the shoulders. The adjacent pair of rollers 56 and 54 and 58 and 54 are arranged opposite to one another and opposite to the rollers of their respective sets for the purpose of guiding the plates as they are moved down the rollers and thus maintain them in alignment on the rollers.

The conveyor 18, unloader mechanism 20, pushing mechanism 22, and cams 88 and 92 are all driven from a source of power, not shown, through power transmitting shaft 136.

The horizontal bars 28 and 30 are controlled respectively for operation through appropriate levers and linkage 138 being engaged by cams 140 and 142 rotatable with shaft 136 for the timed cooperative relation thereof.

The unloading arms 31 of mechanism 20 are actuated by suitable links and levers 144 including crank lever 146 deriving motion from an eccentric 148 affixed to the shaft 136 for rotation therewith.

The pusher mechanism 22 is operated by way of lever 59 deriving motion from a belt crank and link arrangement 150 belt driven from the shaft 136.

The cams 88 and 92 are driven from a gear 152 having driving connection with a gear 154 secured for rotation with the shaft 136.

Through the proper arrangement of the mechanism associated with the shaft 136 to be driven thereby, a proper timed relation of operation

is attained such that the mechanisms operate in a smooth relation to one another in the automatic handling of spring plates from the time of deposit on the conveyor until the completion of the quenching operation thereof.

The dies 14 although of a similar nature with respect to their disposition on opposite sides of the furnace differ in that it is the general purpose to provide dies that handle different size spring plates for the cambering thereof such, for example, as a main leaf spring plate and a number four spring plate of a conventional automotive vehicle leaf spring assembly.

After the dies are arranged with respect to the furnace location and plates that they are to handle, it is then necessary to provide for the operation of the rollers 54 in a direction of rotation that will convey the spring plate therein to the proper place for insertion into one or the other of dies 14. In addition to this it is necessary that the spring plates to be cambered be loaded in proper and alternating relation on the conveyor so that the plate will match the die to which it is to be delivered. This can be accomplished by providing a detector light at the loading station which will inform the loader what plate is to be then placed in the conveyor.

In a normal operation of the combination mechanism 10 wherein the heating elements of the furnace are placed in operation and the power transmitting shaft is driven from its power source thereby effecting operation of the conveyor 18 and mechanisms 20, 22, 24, and 26. With the conveyor in operation it is necessary for an individual to load flat spring plates upon the conveyor bars 28 and 30 alternating two sets of plates, such as, a main plate, number form plate, main plate, and so on. In loading the plates upon the conveyor it is necessary that the plates be deposited synchronously to the operation of rollers 54 so that the proper plates will be delivered to their respective dies and this can be accomplished either through the knowledge of the loader or by means such as a flasher light controlled by the operation of the reversing mechanism for the rollers 54. After the proper loading of the plates and their subsequent passage through the furnace to be heated, the arms 31 of unloaded mechanism 20 lift one plate at a time from bars 28 and 30 and deposits same on slides 32 adjacent the furnace whereupon the fingers 48 on arms 34 of carriage 36 which is coordinated for operation with the conveyor and mechanism 20 engage the plate and push it down the slide onto rollers 54. The rollers 54 at this time will be coordinated for operation so that they will be rotating in the proper direction to transfer the heated plate to its proper die 14. The plate is then moved onto rollers 56 or 58 as the case may be until it moves to the end of the set of rollers and abuts one of the micro-switches 78, said tripping of the switch effecting operation of motor 82 or 112 resulting in actuating arms 62 effective to pick up the plate from the rollers and deposit it into die 14. During the course of this operation the rotation of cam 14 driven from motor 64 provides for the proper lifting action of the arms to pick up the plate and subsequently deposit it on the die and return to their normal position, whereas cam 80 which is set relative to the operation of mechanism 26 trips a switch 156, said switch in turn controlling the operation of the closing of the die upon the deposited plate as well as simultaneously effecting quenching of the die and

75

spring plate in oil tank 16. The cam 16 engages switch 153 effective to stop rotation of motor 64 after a completed operation of mechanism 26.

The next plate removed from the furnace and delivered to rollers 54 is moved to the set of rollers opposite from the previous operation and a like process is carried out relative to switch control and mechanism operation for the cambering and quenching thereof. This alternate conveyance and delivery of plates, one plate to one die and the next to the other die and so on provides for the efficient, and economical handling, heating, cambering, and quenching of two different sets of plates, each requiring an individual die for the cambering thereof, while only using one furnace for the heating of the plates.

The cambering and quenching of a plate of each set of leaf spring plates completes an entire phase of operation of the mechanism.

While this invention has been described in connection with certain specific embodiments, the principle involved is susceptible of numerous other applications that will readily occur to persons skilled in the art. The invention, therefore, is limited only as indicated by the scope of the appended claims.

What I claim is:

1. Combination mechanism for the automatic handling of leaf spring plates in the heating, cambering, and quenching thereof comprising a heating furnace, walking beam mechanism for transporting springs through the furnace in orderly and parallel array, articulating arm mechanism for retrieving the plates from the furnace and for delivery to a point removed from the furnace, a pair of spaced cambering dies arranged forwardly from the exit of the furnace, a pair of quenching tanks, one associated with each die into which the respective cambered plates are moved after a cambering operation, roller mechanism for delivering the retrieved plates alternately in opposite horizontal directions to positions adjacent to the dies, and lifter and conveying mechanism associated with each die for transferring the plates from positions adjacent the die to the die, said mechanisms and dies all being power driven in coordinated timed relation to one another.

2. A machine for the automatic handling of leaf spring plates in the heating, cambering, and quenching thereof comprising a heating furnace, a plurality of cambering dies associated with and spaced apart from each other and from the exit of the furnace, a plurality of quenching tanks, one associated with each of the cambering dies, walking beam mechanism associated with the furnace for conveying the leaf spring plates therethrough that have been manually loaded thereon in prearranged order, articulating arm mechanism for retrieving the plates from the furnace off of the conveyor means one at a time after they have been heated and depositing same adjacent the furnace exit, pusher means for moving the plates after retrieval substantially outside the furnace to a further deposited location, roller means at the further location for delivering the plates alternately to one side or another to a point adjacent one die or another, and means for picking up the plates from the delivery means and inserting the plates in the die with which they are associated, said cambering dies conveying and retrieving mechanisms and means each being power driven in coordinated timed relation to one another.

3. Mechanism for carrying out the heating, cambering, and quenching of leaf spring plates in

an automatic manner comprising a heating furnace having a horizontal passage therethrough between the entrance and exit thereof, a pair of cambering dies arranged in spaced relation opposite the exit of the furnace, a pair of oil quench tanks one associated with each of the dies into which the plates are to be moved after a cambering operation, horizontally arranged walking beams means for conveying the plates through the horizontal passage in the furnace in singular parallel array, mechanism for delivering the plates singularly in alternate relation to one die or another from the exit of the furnace comprising arm members for retrieving the plates from the furnace one by one after being heated, arm means for pushing the plates down a pair of parallel slide bars after retrieval, roller means for receiving the plates after sliding down the bars and delivering same in a horizontal direction to a point adjacent one die or another as the phase of motion dictates, and pusher means for picking up the plates from the delivery means and inserting same in the dies, said dies, conveying means, and delivery mechanism all being operated in coordinated relation to one another in accordance with prearranged loading of the plates in the furnace on the conveying means.

4. Mechanism for the automatic handling of leaf spring plates in the conveying thereof from a heating furnace to two dies associated therewith spaced apart from one another comprising articulated arm means for retrieving the spring plates from the furnace after the heating thereof, reciprocated arm means for pushing the plates to a position beyond the retrieved point, roller means for moving the plates alternately in one direction or another adjacent one die or another after their retrieval from the furnace, and arm means operating perpendicular to the roller means associated with the delivery means for inserting the plates into the die with which they are associated, said dies and means all being power driven in coordinated relation to one another.

5. A combination machine for the automatic handling of leaf spring plates in the heating, cambering, and quenching of two different types of plates, each requiring a separate cambering die, comprising a heating furnace, two cambering dies, suitably spaced from the exit of the furnace, a pair of quench oil tanks one associated adjacent and with each die, automatic walking beam conveyor means for transporting the spring plates through the furnace in orderly parallel array, reciprocable mechanism for retrieving the plates from the furnace as they approach the exit thereof, mechanism for delivering the plates after being retrieved from the furnace to the dies for the cambering thereof comprising a plurality of roller means arranged in a horizontal aligned array extending along between and in front of the furnace exit and dies means for alternately delivering the plates adjacent the dies, reciprocable arm means for removing the plates from the rollers and inserting the plates in the dies, means for actuating the dies and for moving the dies into their associated quenching tanks during the cambering operation, power means for actuating the conveyor means, mechanisms, and dies, and control cams and switches associated with the power means, conveyor means, dies, and mechanisms for the coordinated operation thereof.

6. Mechanism for the automatic handling of leaf spring plates in the conveying thereof from a heating furnace after the heating thereof to two dies associated therewith and spaced there-

from and apart from one another in parallel array to the exit from the furnace comprising a pair of parallel slide bars extending from the furnace exit to a point removed therefrom, articulating arm means for transferring the plates from the furnace exit to a point on the slide adjacent the furnace exit, reciprocable pusher means for moving the plates down the slide bars, a plurality of rollers aligned side by side extending between the dies and across and perpendicular to the slide bars, a number of said rollers rotatable in both directions for alternately moving the plates after delivery thereto to a point adjacent one or the other of the dies, and reciprocable arm means associated with each of the dies for transferring the plates delivered adjacent the dies from the rollers to the dies.

7. Mechanism for the automatic handling of leaf spring plates in the conveying thereof from a heating furnace after the heating thereof to two dies associated therewith and spaced therefrom and apart from one another in parallel array to the exit from the furnace comprising a pair of parallel slide bars extending from the furnace exit to a point removed therefrom, articulating arm means for transferring the plates from the furnace exit, reciprocable pusher means for moving the plates down the slide bars, a plurality of rollers aligned side by side extending between the dies and across and perpendicular to the slide bars, a number of said rollers rotatable in both directions for alternately moving the plates after delivery thereto to a point adjacent one or the other of the dies, reciprocable arm means associated with each of the dies for transferring the plates delivered adjacent the dies from the rollers to the dies, and means for operating in timed sequence the articulating arms, pusher, reciprocable arm means, and the rollers.

8. Mechanism for the transferring of heated metallic articles from a heating furnace to a pair of spaced in line dies lying parallel to and spaced from the exit of the furnace comprising a plurality of rollers extending in alignment along and in front of the dies and furnace exit with their axes lying parallel to one another, slide bars extending from the furnace exit to a point adjacent a central group of the rollers, 5 said central group of rollers being rotatable in both directions and the groups of rollers on either side of the central group being rotatable solely in one direction opposite to each other, a pair of articulating arms for picking the articles from the furnace and depositing same at the end of the slide bars adjacent the furnace exit, a pair of reciprocable arms for pushing the articles down the slide bars to the central group of rollers, and a pair of articulating arms associated with each die for transferring the articles 10 from the group of rollers on one end associated therewith to the dies.
